UNITED STATES PATENT OFFICE.

ANGELINA U. LUCA, OF MERIDEN, CONNECTICUT.

DESIGN FOR A WINDOW-SHADE.

57,846.

Specification for Design.

Patented May 10, 1921.

Application filed November 19, 1920. Serial No. 425,270. Term of patent 14 years.

To all whom it may concern:

Be it known that I, ANGELINA U. LUCA, a subject of the King of Italy, residing at Meriden, in the county of New Haven and State of Connecticut, have invented a new, original, and ornamental Design for a Window-Shade, of which the following is a specification, reference being had to the accompanying drawings, forming a part thereof.

The figure is a plan view of the window shade showing my new design.

I claim:

The ornamental design for a window shade as shown.

ANGELINA U. LUCA.
